UNIVERSAL PAINT STRIPING DEVICE

Karl V. Eklov, Detroit, Mich.

Application June 13, 1933, Serial No. 675,584

4 Claims. (Cl. 91—62.6)

My invention relates to a paint striping device, and is an improvement over my former striping device as described in my former application Serial No. 625,741, filed July 29, 1932.

5 The object of my invention is to produce a universal striping device adapted for making fine striping lines on various positioned surfaces, the striping device being capable of functioning in several different positions.

10 Another object is to produce a paint striping device having the liquid paint container rotatably mounted on the striping unit and capable of complete rotation thereon to any position about the striping axis.

15 A further object is to produce a striping device having an angularly positioned paint container attached to the mounting collar by swiveled means, capable of inclining said container in any desired direction with the striping axis, for causing the liquid paint to flow therethrough for the various positions of the striping unit.

20 A still further object is to produce a universal paint striping device provided with an automatic feed valve for controlling the flow of liquid paint when the striping device is not in use, actuated by an adjustable guide member connected thereto.

25 Another object is to produce a universal paint striping device that is simple in construction, easily and efficiently operated and that can be manufactured at a very low cost.

30 These several objects are attained in the preferred form by the construction and arrangement of parts as are more fully hereinafter set forth.

35 It is to be pointed out that while the general principle of the striping unit per se, is similar to that of my former device referred to in the aforementioned patent application, it is improved and modified by the universal and automatic features of both the rotatable feed collar and attached swiveled paint container, together with the automatic feed valve and connected movable guide, and my invention herein resides principally in the new combination of these units and their connected operating elements.

Similar parts on all drawings are marked by similar numerals or letters.

40 Fig. 1 is a side view of my improved universal striping device showing the general arrangement of the exterior parts.

45 Fig. 2 is an end view of the assembled unit showing the relative position of the adjustable guide unit and the movable supporting thimble.

50 Fig. 3 is a top view of the same assembled

unit showing the relative positions of the various operating units and liquid paint container.

5 Fig. 4 is an end view taken on the line 4—4 of the Fig. 1 showing the rotatably mounted feed collar and attached paint container, and means for retaining same on the striping unit.

Fig. 5 is a vertical sectional view taken on the line 5—5 of Fig. 3 showing the relative position of all of the interior and exterior operating parts when the striping device is not in use, and the paint container passage closed.

10 Fig. 6 is also a vertical sectional view taken on the same section line 5—5 of Fig. 3 showing the relative position of the operating parts when the striping device is in use and the adjustable guide 15 thimble displaced for automatically opening the paint container feed valve.

Fig. 7 is a cross sectional view taken on the line 7—7 of Fig. 6 showing the paint liquid channels and the control valve mounted therethrough.

20 Fig. 8 is a cross sectional view taken on the line 8—8 of Fig. 6 showing the splined means for mounting the guide supporting thimble thereon.

Fig. 9 is a detail view of the liquid channel feed valve showing a grooved valve passage formed 25 therein.

Figs. 10 and 11 show modified forms of valve members formed with port passages therethrough instead of external grooved passage shown in Fig. 9, and may be substituted therefore.

30 Fig. 12 is a side view of the rotatably mounted feed collar showing the liquid paint container as swivelly mounted thereon by means of a threaded nipple end, also capable of being turned therein to any desired position.

35 In general my device comprises a tubular paint striping unit, of any chosen design or type, but formed with a centrally located liquid paint passage aximetrically therethrough, and provided with an annular feed ring rotatably mounted on the inner end thereof. The feed ring carries a paint container swivelly mounted thereon and formed with a liquid paint passage opening into the striping unit central passage, and is provided with a regulating valve therein actuated by displacement of a movably mounted guide unit along the striping unit nib.

40 I will now describe more fully the detail construction of my device, referring to the drawings and the marks thereon.

45 The striping unit 1 is made of metal comprising the nib *a* and the body section *b* which is preferably formed of a series of stepped cylindrical sections *c*, *d* and *e*, all concentric about the same axis. The nib *a* is formed with a 50

short cylindrical disc chamber *f*, open at the nib end, and carries rotatably mounted therein a pinned surface striping disc *g*, said disc having one edge projected out of the edge opening of the inclosing chamber *f*. A curved disc spring *h* is also mounted within the disc chamber *f*, partially surrounding the disc *g*, the spring ends coming in contact with the pinned disc surface at the chamber opening. A central paint channel *k* is formed lengthwise through the body section *b*, positioned concentric with the striping unit axis and leads into the disc chamber *f*. A more detailed description of the preferred striping nib herein shown, is set forth in my former patent application, Ser. No. 484,283, filed September 25, 1930, and while I illustrate a similarly constructed striping nib in this invention, it is to be understood that any other suitable type of striping nib might be substituted therefore in this described improvement. Slidably mounted on the outer surface of the striping unit body *b*, is a hollow guide thimble 2, also made of metal and preferably formed in a cylindrical shape having an end flanged collar *i*, and formed with an inner end shoulder *l* around the inner end thereof, said shoulder *l* fitting over and slidably mounted on the cylindrical body section *c* of the striping unit, the sliding movement thereon being limited by the adjacent cylindrical body section *d*. The outer end of the guide thimble 2 being slidably mounted over the end body section *e*, and thereby forming a chamber recess *m* between the surfaces of the thimble 2 and the inclosed striping unit body *b*. Within the recess chamber *m* is mounted a compression coil spring 3 which engages the oppositely positioned end shoulders *l* and *e* of the guide thimble 2 and striping unit 1 respectively, the reaction of said spring retaining the engaged members in an open position when unrestrained by manual pressure thereon, as indicated in the Fig. 5 of the drawings.

Slidably mounted over the cylindrical guide thimble 2, and splined thereto, is an adjustable guide frame 4 which is more specifically described in my guide patent application Serial No. 680,049, filed July 12, 1933, and is herein shown to illustrate any suitable type of adjustable striping guide as may be mounted thereon for forming contact with a guide rail or template for guiding the striping device over painted surfaces on which stripe lines are to be made. The guide unit 4 herein shown comprises a thimble block *n* formed with a cylindrical hole *p* therethrough for fitting and sliding over the guide thimble 2, the top edge of the block being slotted and the section tightly clamped to the thimble 2 by the threaded bolt and nut 5 and 6 mounted therein. A key 7 is formed on the outer surface of the thimble 2 and engages a corresponding key recess through the thimble block *n*, allowing a longitudinal adjustment thereon. An adjustable guide block *r* having slide rods *s* fixedly mounted on opposite sides thereof, is slidably mounted on the lower side of the thimble block *n* and clamped thereto in any adjusted position by contact of the threaded bolt and nut 5 and 6 which engage the surface of the slide rods *s* when screwed together. Guide arms 8 with ball tipped ends are rigidly mounted on the outer face of the guide block *r*, positioned at right angles thereto, and adjusted, when in a released position, with the ball tips slightly back of the striping nib disc *g*, as shown in the Fig. 5 of the drawings. The guide block *r* and attached arms 8 may be ad-

justed as required to engage any guiding ridge or template edge *u* as may be used or provided on the surface to be painted. Through the inner end of the striping unit body section *c* is formed a key recess *v* and which carries a curved key bar 9 mounted therein, said key bar ends being projected outside of the body walls and engage corresponding key ways formed in the shouldered end section *l* of the guide thimble 2, thus preventing any rotation of the striping unit within the thimble, yet free to slide lengthwise thereof. The inner end of the paint passage channel *k* is threaded and carries mounted therein a cylindrical stud hub 10 with threaded end tightly screwed therein, positioned concentric with the striping unit axis. The hub 10 is formed with a cylindrical body *w* having an annular feed groove *x* positioned near the center thereof, and provided with radially positioned port holes *y* opening into a centrally positioned passage channel *z* which is extended aximetrically through the hub 10 and opens into the striping unit channel *k*. The hub 10 is provided with a recessed end head 11, and carries mounted therein an irregular shaped spring washer ring 12. Rotatably mounted on the channel hub 10 is a cylindrical shaped feed collar 13, fitted thereto and free to rotate thereon to any desired position about the axis of the striping unit 1, and is retained in such chosen position by the spring pressure of the spring washer ring 12 which engages therewith. The feed collar 13 is provided with a side hub 14, and is formed with a paint passage 15 positioned radially therethrough, opening directly into the annular groove *x* of the hub channel 10. On the outer end of the hub 14 is mounted a hollow paint container 16, preferably formed pear shaped, positioned at a chosen angle with the striping unit axis, and is swively connected to the hub 14, preferably by a swivel joint as illustrated in Fig. 6 of the drawings, or may be connected by a threaded stud 17 as illustrated in Fig. 12 of the drawings, the container 16 being capable of one complete rotation about the connecting joint. The container tank 16 is provided with a threaded cap 18 at the upper end thereof for filling and closing the tank with liquid striping unit, and is formed with a small outlet port 19 through the swivel joint connection, and opening into the feed collar hub channel 15, providing a continuous passage channel from the container 16 to the striping nib disc *g*, for all positions of both the container 16 and feed collar 13. Through the collar 14, is slidably mounted a feed control valve 20, preferably formed of a cylindrical body section *a'*, having a centrally positioned annular valve groove *b'* and an end operating groove *c'* formed therein, although the modified forms as illustrated in Figs. 10 and 11 may be used if desired, said control valve 20 being positioned through the hub 14 parallel to the axis of the channel hub 10, and mounted with the end operating groove *c'* engaging the end collar *i* of the guide thimble 2 while the central annular valve groove *b'* or port *b''* is positioned at one side of the paint passage 15 when the guide thimble is unstrained, as indicated in the Fig. 5 of the drawings, the valve stem *a'* completely closing the paint passage 15, preventing leakage of the liquid paint from the container 16 when the device is not in use.

When the paint container 16 is filled with the desired striping paint, the user in applying the device will hold the striping unit in his finger tips

by grasping the sides of the guide frame 4, then placing the contact edge of the striping disc *g* against any painted surface *t*, as indicated in the Fig. 5 of the drawings, and applying pressure thereto sufficient to displace the striping unit body *b* within the thimble 2 as illustrated in the Fig. 6 of the drawings, and which also displaces the connected feed control valve 20 within the hub 14 by reaction of the connecting 5 guide thimble flange *i*, opening the paint passage 15, allowing the striping paint to flow through the connecting channel passages directly to the striping disc *g*. The stiper is operated in the ordinary manner by moving the device along the painted surface *t*, rolling the striping disc *g* thereon, the control valve being held open as long as pressure is applied to the guide frame 10 unit, but closes as soon as the pressure is released, the valve and striping unit returning to its closed position as shown in Fig. 5, under reaction of the inclosed spring 3.

The operating valve end groove *c*' being fitted over the flange *i* of the thimble collar 2, allows the feed thimble 13 and connected paint container 16 to be rotated about the hub 10 to any desired position so as to retain the container above the striping unit 1 causing a gravity feed for the paint liquid therethrough for any position of the stiper. The swiveled paint container 30 as connected to the hub collar 14 also provided a further adjustment of the tank 16 when the stiper is being used on vertical or inclined surfaces, the container being turned to a forward position as indicated by the dotted position 16' 35 in the Fig. 5, retaining the paint supply above the stiper nib disc *g*.

While I have illustrated the preferred design of my universal striping device, it is to be understood that various modifications in both general design and mechanical elements may be made without departing from the spirit of my invention, that any suitable type of paint striping nib, guide frame or operating valve may be substituted for the respective parts shown herein, and I claim the design as heretofore described and illustrated and any other design that is substantially a substitution of the various parts and units herein shown.

Having fully described my universal paint striping device, what I claim as my invention and desire to secure by Letters Patent is:

1. A universal paint striping device adapted for making stripe lines on smooth surfaces for all positions of the stiper, comprising a paint striping nib formed of an elongated body section and having a striping disc rotatably mounted in the outer end thereof, said nib body being provided with a central paint channel lengthwise therethrough leading to the striping disc, an external casing member 55 slidably mounted over the said nib body and splined thereto and provided with an intermediately positioned spring member capable of retaining said external casing in a predetermined position on the nib body, a liquid paint container attached to a mounting collar rotatably mounted on the inner end of the striping nib body, capable of a complete rotation thereon and provided with a paint channel therethrough opening into the central paint channel of the stiper nib body for all of the rotatable positions of the container thereon, a paint feed control valve operatively mounted through said container mounting collar intercepting the paint passage channel leading therethrough, said operating valve being 60 connected with and actuated by the slidably 65

mounted external casing member when said casing is displaced along the striping nib body.

2. A universal paint striping device adapted for making stripe lines on smooth surfaces for various positions of the striping device, comprising an elongated cylindrical bodied paint striping nib having a striping disc rotatably mounted with one end thereof and a cylindrical shouldered end formed on the opposite end thereof, said nib body being provided with a central paint passage channel positioned lengthwise therethrough and leading to the striping disc, a cylindrical guide thimble slidably mounted over the nib body and splined thereto, guide members mounted on said cylindrical guide thimble adjustable to the said striping disc, a spring member mounted between the guide thimble and nib body for retaining them in predetermined relative positions one with the other, a paint container attached to a mounting collar rotatably mounted on the cylindrical shouldered end of the paint striping nib body, capable of complete rotation thereon, said container being positioned at an angle with the axis of the nib body and is provided with a paint passage channel therethrough opening into the central paint channel of the striping nib body for all rotatable positions of the container therearound, an operating valve slidably mounted through the container mounting collar intercepting the paint channel leading therethrough, said operating valve being directly connected to the cylindrical guide thimble of the nib body, and actuated for opening and closing said paint channel by longitudinal displacements of said thimble along the nib body.

3. A universal paint striping device adapted for making stripe lines on smooth surfaces for various positions of the stiper, comprising an elongated cylindrical bodied paint striping nib formed with a striping disc rotatably mounted in one end thereof and with a cylindrical shouldered section on the opposite nib body end, said nib body being provided with a paint passage channel lengthwise therethrough leading to the striping disc, a cylindrical guide thimble slidably mounted over the said nib body, splined thereto and provided with a spring member for retaining said thimble in a pre-determined position on the nib body, a paint container swivelly attached to a mounting collar, positioned thereon at an angle with the nib body axis and capable of rotation to various positions about the swiveled connection, said mounting collar being rotatably mounted on the cylindrical shouldered end of the striping nib body, rotatable to all positions thereabout, and provided with a paint passage channel therethrough opening into the central paint channel of the nib body for all rotated positions thereon, a feed control valve slidably mounted through said mounting collar intercepting the paint channel and positioned to connect with the guide thimble for all positions of the container and feed collar, and actuated thereby for opening and closing said paint channel by longitudinal displacement of the guide thimble along the stiper nib body.

4. A universal paint striping device adapted for making stripe lines on smooth surfaces for various positions of the striping device, comprising a paint striping nib body formed of shouldered, cylindrical body section having a striping disc rotatably mounted in one end thereof and formed with a cylindrical shouldered opposite end, said striping nib body being provided with a central paint channel lengthwise therethrough leading

to the striping disc, said cylindrical shouldered end being formed with a central annular groove with radially positioned port passages opening into the nib central paint channel, a cylindrical 5 guide casing with one shouldered flanged end slidably mounted over the nib body and splined thereto, said guide casing having guide arms mounted thereon, a coil casing mounted between the guide spring and nib body engaging with their 10 respective shouldered end sections for retaining said members in a pre-determined relative position, a paint container with swivelly attached mounting collar rotatably mounted on the shoul-

dered end of said nib body capable of a complete rotation thereon and provided with a paint passage therethrough opening into the end annular paint groove, a control valve slidably mounted through the container mounting collar intercepting the paint passage, said control valve being slotted at its outer end for engaging the guide casing end flange and slide thereover for all rotated positions of the container mounting collar, and actuated for opening and closing the valve 10 with the paint channel passage as said guide casing is displaced along the supporting nib body.

KARL V. EKLOV.
